UNITED STATES PATENT OFFICE.

FRANK M. WEIMER AND ROBERT F. WEIMER, OF SOMERSET, PENNSYLVANIA.

MAIL RECEPACLE.

1,109,491.

Specification of Letters Patent.

Patented Sept. 1, 1914.

Application filed August 2, 1913. Serial No. 782,736.

To all whom it may concern:

Be it known that we, FRANK M. WEIMER and ROBERT F. WEIMER, residents of Somerset, in the county of Somerset and State of Pennsylvania, have invented certain new and useful Improvements in Mail-Receptacles; and we do hereby declare the following to be a full, clear, and exact description of the invention, such as will enable others skilled in the art to which it appertains to make and use the same.

This invention relates to improvements in mail receptacles and more particularly to structures of this class, which are adaptable for use in rural mail service,—the object of our present invention being to provide simple and efficient means to facilitate access to the mail box by the carrier.

A further object is to provide means for supporting and manipulating a mail box, which shall be operable by a carrier seated in a vehicle, to project the box from a post or other support to position where it shall be readily accessible to the carrier and lock it in such position and to automatically raise the cover of the box while it is being thus projected.

A further object is to provide simple and effective means for projecting a mail receptacle outwardly from a post or other support and automatically locking the same uncovered in such projected position, and to provide devices for releasing the projecting devices and for effecting return of the box to normal position.

With these and other objects in view, the invention consists in certain novel features of construction and combinations of parts as hereinafter set forth and pointed out in the claims.

In the accompanying drawings, Figure 1 is a perspective view illustrating our improvements; Fig. 2 is a sectional view of the same; Fig. 3 is a rear view, partly in section, showing the receptacle; Fig. 4 is a detail view partly in section, showing the slide 6 and means for moving the same in one direction; Fig. 5 is a detail sectional view showing the slide 6 and the spring which moves it in one direction; Fig. 6 is a view, partly in section, showing the receptacle projected; Fig. 7 is a sectional view of the receptacle, with the cover raised; Fig. 8 is an enlarged transverse sectional view; Fig. 9 is an enlarged plan view, showing the bracket 3, and Fig. 10 is a plan view of the

slide 6 showing the connection of the spring and guide rod therewith.

1 represents a post or other support on which a mail box or receptacle 2 is mounted, through the medium of instrumentalities hereinafter described for projecting said box outwardly and disposing in position which shall be readily accessible to the carrier while he is seated in his vehicle. Upon the post 1, a horizontally disposed U-shaped bracket 3 is secured preferably by means of depending arms 4. This bracket is of sufficient length to project some distance outwardly from the post and the inner edges of its parallel members are made with beads or guides 5 which enter grooves in the side edges of a slide 6 disposed between said parallel members of the bracket.

Two levers 7—8 are pivotally mounted short distances from their inner ends upon the bracket 3 and project outwardly in opposite directions from such pivotal mountings. The weight of these outwardly projecting levers and of the devices (hereinafter described) mounted upon them, is sustained by trackways 9 secured to the bracket 3, the levers having brackets 10 depending from them and carrying rollers 11 to run on said trackways. To the outer end of the lever 8, one end of an arm or bar 12 is pivotally attached, the other end of the latter being rigidly secured to the bottom of the mail box or receptacle 2 by means of suitable bolts. To the outer end of the lever 7, one end of an arm or bar 13 is pivotally attached, the other end of the latter being pivotally attached to the bottom of the mail box or receptacle at or near the center thereof.

From the above construction and arrangement of parts, it will be seen that if the levers 7—8 be turned in one direction on their pivotal supports, the outer ends of said levers would be moved outwardly and the mail box would be projected outwardly from the post, and that as the arm or bar 12 is rigidly secured to the box and the arm or bar 13 pivotally attached thereto, the box will be turned during its outward movement and thus brought to position in front of the carrier so that he may have ready access thereto without leaving or reaching out of his vehicle. With the parts connected as shown in the drawings, the box will be turned in one direction to accommodate a carrier riding in one direction along the

roadway. It is apparent that the box may be caused to turn in the reverse direction to accommodate a carrier riding in the opposite direction, by securing the arm or bar 12 at the other end of the box and pivoting it to the lever 7 and connecting the arm or bar 13 with the lever 8.

The inner ends of the levers 7-8 are curved and made to overlap, said overlapping ends being provided with elongated slots 14 to receive a pin 15 carried by the slide 6. A rod 16 is secured at one end to the slide (under the same) and the other end of this rod passed freely through a hole in an arm 17 depending from the rear end of the bracket 3. A spring 18 encircles the rod 16 and bears at one end against the arm 17, the other end of said spring bearing against a washer on the rod, and thus tends to move the slide in one direction.

Lugs or ears 19 depend from the members of the U-shaped bracket 3 near the forward ends of the same, and between these lugs, a lever 20 is pivotally supported. The short arm 21 of this lever projects upwardly from the pivotal support thereof and is preferably made with a curved or beveled face to engage the forward end of the slide 6, while the long arm of said lever depends a considerable distance and is provided at its free end with a hook 22 to be engaged by a suitable device in the hand of the carrier seated in the vehicle, for operating said lever to move the slide 6 and thus actuate the levers 7-8 to project the mail box as previously explained.

The mail box may be provided with a guide rail 23 for the pivoted arm or bar 13, and to one end of said box, a latch 24 is pivotally attached so as to engage the adjacent arm or bar when the mail box is projected, and thus lock the box in its projected position.

The box 2 is provided with rearwardly projecting ears 25 to which a cover 26 is hinged and these ears may be provided with upward projections 27 to form stops for said cover when the latter is open. The cover thus projects beyond the rear wall of the box and is engaged by the curved upper end of a lever 28. This lever is pivoted between its ends to the back of the box, and its lower end is forked or bifurcated as at 29. A guide 30 may be provided on the back of the box for the lever 28 and the lower bifurcated end of said lever is adapted to project somewhat below the plane of the bottom of the box. By turning the lever 28 on its fulcrum, its curved upper end will engage the rearwardly projecting portion of the cover and raise the latter. In order that the cover shall be raised to a suitable height, the curved end of the lever is provided with a laterally projecting pin 31 which will engage the under face of the cover and raise the lat-

ter higher than it could otherwise be raised by the lever. The lower bifurcated end 29 of the lever 28 is normally in position to receive the arm or bar 13 when the devices are operated to project the box. Thus, while the arm or bar 13 is moving outwardly during the operation of projecting the box, said arm 13 will enter the bifurcated end 29 of the lever 28 and turn said lever on its fulcrum to effect the raising of the cover.

A target 32 is pivoted to one end of the box or receptacle 2 and is provided with an inclined open slot 33 to engage a pin 34 on one end of the cover 26. This target is intended to indicate when in an upright position, that the box contains mail matter to be collected by the carrier. When the cover is raised as above explained, the pin 34 will be moved out of the slot 33 in the target and thus release the latter.

It will be apparent from the construction and arrangement of parts herein described, that when a carrier, seated in his vehicle, pulls the lever 20 outwardly, the mail box will be projected toward him and properly turned toward him to permit ready access; that during such movements of the box, its cover will be raised, and that the box will be automatically locked in its projected position. During the operation of projecting the box, the spring 18 will be brought under tension, so that when the carrier operates the latch (the latter being provided with a finger piece 35 for this purpose) to release the parts, the box will be returned by the action of said spring, to its normal position. During such return of the box, the arm or bar 13 coöoperating with the bifurcated lever 28, will cause the cover to be closed down.

In order to protect the bearings for the slide 6 and the parts connected with said slide from dust, etc., a cover plate 36 may be provided and secured to the bracket 3.

Various slight changes might be made in the details of construction of our invention without departing from the spirit thereof or limiting its scope and hence we do not wish to restrict ourselves to the precise details herein set forth.

Having fully described our invention what we claim as new and desire to secure by Letters-Patent, is:-

1. The combination with a suitable support and a receptacle, of two levers mounted on said support, arms pivoted to said levers and both of said arms connected directly with said receptacle at points separated from each other, and means for operating said levers to project the receptacle.

2. The combination with a support and a receptacle, of two levers mounted on said support, arms pivotally attached to said levers, one of said arms being pivotally attached to the receptacle and the other arm being rigidly secured to said receptacle, and

- means for operating said levers to project said receptacle and simultaneously turn it in a horizontal plane.
3. The combination with a support, a receptacle, and a hinged cover for the latter, of mechanism for projecting said receptacle from the support and simultaneously turning it in a horizontal plane, and devices cooperating with said projecting and turning mechanism for raising said cover.
4. The combination with a support, and a receptacle, of levers mounted on said support, arms pivoted to said levers and connected with said receptacle, a slide connected with said levers, a lever for moving said slide in one direction to project the receptacle from the support, and means for moving the slide in the reverse direction to return the receptacle to normal position.
5. The combination with a fixed bracket, and a receptacle, of a slide mounted in said bracket, levers pivoted to said bracket and connected with said slide, arms pivoted to said levers and connected with said receptacle, a lever pivotally supported by the bracket and having an arm to engage said slide for moving it in one direction to project the receptacle.
6. The combination with a bracket and a receptacle, of a slide mounted in the bracket, levers pivoted to said bracket and connected with said slide, arms pivoted to said levers and connected with the receptacle, a lever pivotally supported by the bracket for moving the slide in one direction, and a spring interposed between the bracket and slide for moving the latter in the reverse direction.
7. The combination with a support, a receptacle, and a hinged cover for the receptacle, of levers pivotally mounted on the support, means for operating said levers, arms pivoted to said levers and connected with a receptacle, a lever pivotally connected with the receptacle and adapted to engage the cover for raising it, said last-mentioned lever having a bifurcated part to be engaged by one of said arms for operating said lever.
8. The combination with a support, and a receptacle, of spring-actuated levers pivotally mounted on said support, means for operating said levers, arms pivoted to said levers and connected with the receptacle, and a latch on the receptacle in position to engage one of said arms when the receptacle is projected to retain the receptacle in projected position against the retractile action of said spring-actuated levers.
9. The combination with a support, and a receptacle, of levers pivotally mounted on said support, arms pivoted to said levers and connected with the receptacle, means for operating said levers, a fixed trackway, and rollers carried by said levers and adapted to run on said trackway.
10. The combination with a support, a receptacle and a hinged cover for the latter, of levers mounted on the support, arms pivoted to said levers and connected with the receptacle, means for operating said levers, and means co-operative with one of said arms and the cover for raising the latter.

In testimony whereof, we have signed this specification in the presence of two subscribing witnesses.
